UNITED STATES PATENT OFFICE.

CHARLES A. BROWN, OF GARDNER, MASSACHUSETTS, ASSIGNOR, BY MESNE ASSIGNMENTS, TO HEYWOOD-WAKEFIELD COMPANY, OF BOSTON, MASSACHUSETTS, A CORPORATION OF MASSACHUSETTS.

COMBINED HINGE AND STOP FOR DESK LIDS AND THE LIKE.

1,423,513.

Specification of Letters Patent. Patented July 25, 1922.

Application filed November 20, 1919. Serial No. 239,407.

To all whom it may concern:

Be it known that I, CHARLES A. BROWN, a citizen of the United States, residing at Gardner, in the county of Worcester and 5 Commonwealth of Massachusetts, have invented a new and useful Improvement in a Combined Hinge and Stop for Desk Lids and the like, of which the following, together with the accompanying drawings, is 10 a specification.

The present invention relates to an improved form of hinge device for use particularly in connection with the lids of desks. The invention resides in a construction of 15 the stationary and movable parts of the hinge, and in the arrangement of said parts relative to the sides, top and lid of the desk, or other hinged article, whereby simplicity, strength and ease of attachment is secured, 20 and at the same time the necessity for any independent stop or limiting member for the lid is eliminated. The above and other objects are obtained by the form of hinge hereinafter described, reference being had to 25 the accompanying drawings, in which—

Fig. 1 is a perspective view of the hinge, with the desk lid in open position.

Fig. 2 is a section through the desk top and lid, showing the hinge in side elevation, 30 with the desk lid in closed position.

Fig. 3 is a sectional view at right angles to the plane in which the section of Fig. 2 is taken.

Fig. 4 is a detached view of the stationary 35 member of the hinge, and

Fig. 5 is a detached view of the movable member of the hinge.

Like reference characters refer to like parts in the different figures.

40 In the drawings only so much of the desk structure is shown as is necessary to illustrate the construction and operation of a single hinge device, but it will be understood that the desk is provided with two 45 such devices, one associated with each of the desk sides 1, 1. As is usual in desks of this class, the sides 1, 1, of which one only is shown, have secured thereto a top board 2 which covers a part of the space inclosed by 50 the sides, back, front and bottom of the desk. The closure of the remainder of this space is effected by a swinging lid 3, which in the present instance is hinged by the use of the

duplicate hinge devices constituting the subject matter of the present invention.

55

The stationary member of my improved hinge device, as shown in Fig. 4, comprises a stamped or pressed metal plate of approximately segmental shape, designated as a whole by the numeral 4. The body or flat portion of plate 4 is adapted to bear against the inner surface of desk side 1, being provided with a hole 5 to receive a screw 6 which secures the plate in place. The plate 4 is prevented from turning or rocking on the screw 6 by the provision of an inwardly directed lateral ear 7, which makes contact with the under side of the top board 2, and is secured to said top board by a screw 8. In this way the stationary member of the hinge is held firmly in place by being attached both to the side of the desk and to the top thereof, with the result that the hinge is greatly strengthened and reinforced.

75

The pivotal axis of the hinge, with reference to the stationary member 4, is provided at or near the top of an upwardly extending projection 9, in the same plane as the flat portion of plate 4 that bears against the desk side 1. This projection 9 is received within a narrow slot or saw-cut 10 formed in the edge of top board 2, as shown in Fig. 1. Lying adjacent the projection 9 in the slot or saw-cut 10 is a similarly shaped projection 11 of movable hinge member 12, illustrated in Fig. 5. The projections 9 and 11, lying side by side in contact, are pivotally connected by a pin or rivet 13 that passes through suitably alined holes 14, 14' and thus secures the movable and stationary hinge members together.

80

The movable member 12 of the hinge is a plate of stamped or pressed metal substantially triangular in shape, and with reference to the body or flat portion of plate 12, the projection 11, hereinbefore referred to, is offset in a vertical plane that is nearer the desk side 1. In other words, the body portion of plate 12, when the two parts of the hinge are assembled, is spaced inwardly some distance from the flat or body portion of plate 4; this spacing enables the plate 12 to clear the screw 6 by which the plate 4 is secured to the desk side 1. The plate 12 has an inwardly extending lateral ear 15,

85

105

which is secured by screws 16 to the desk lid 3. In this simple manner the hinge is secured to the side, top and lid of the desk 1, it being clear that the construction is such 5 that all the attaching screws are exposed and readily available, and the construction such that there is no necessity for countersinking the screw 6 that secures the stationary member of the hinge to the desk side 1.

10 The curved lower edge of the plate 4, below the screw 6, is flanged inwardly as shown at 17, so that when the hinge is assembled, the plane of the flange 17 is contiguous to the plane of the body portion of 15 movable member 12, i. e., removed or spaced from the inner surface of desk side 1. For cooperation with the flange 17, the plate 12 provides a doubled over lip 18 that embraces the edge of said flange. In the movement of 20 the plate 12 relative to the plate 4 about the pin 13, the lip 18 and flange 17 cooperate to hold the parts in proper alinement, so as to prevent sidewise rocking or lost motion between the parts. At the forward end, the 25 flange 17 has an overturned lip 19 that serves as a stop in the path of lip 18 when the desk

lid is swung open, and positively limits the further opening movement of said lid.

I claim,

1. A hinge for the movable lid of a desk, 30 said hinge having a stationary element attached to and bearing against the desk side, with the free edge of said stationary element offset from the plane of attachment, and a movable hinge element secured to the 35 desk lid and providing a portion embracing the offset edge of said stationary element.

2. A hinge for the movable lid of a desk, 40 said hinge having a stationary element bearing against the desk side, with its edge removed or offset therefrom, and a movable element secured to said lid and providing a portion embracing the offset edge of said stationary element, said portion cooperating with a stop on said stationary element to 45 limit the opening movement of said lid, said movable element being removed from the plane of attachment of said stationary element, whereby to clear the attaching means of said stationary element. 50

Dated this 7th day of November, 1919.

CHARLES A. BROWN.
